UNITED STATES PATENT OFFICE.

JOHN HARRISON, OF ROXBURY, MASSACHUSETTS.

CAMP CONVENIENCE CHAIR.

Application filed April 5, 1926. Serial No. 99,713.

This invention relates to an improvement in portable or so called camp stools and toilet seats.

The object of my invention is to provide 5 a combination camp stool and toilet seat.

Another object of my invention is to provide a chair that may be used interchangeably either as a stool or a toilet seat.

Another object of my invention is to provide 10 a combination stool and toilet seat which is capable of being easily folded or set up when desired.

Another object of my invention is to provide 15 detail and specifically claimed. Reference will now be had to the drawing forming a part of this application, wherein there is illustrated a preferred embodiment of my invention, but it is understood that the elements thereof can be varied or changed as 20 for shape, size or form without departing from the spirit of the invention.

In the drawings:—

Fig. 1 is a side view of the stool, in its set 25 up position.

Fig. 2 is an end view of the stool in its set up position.

Fig. 3 is a plan view of the device when used as a tool.

Fig. 4 is a plan view of the device showing 30 the toilet seat arrangement.

Fig. 5 shows the device in its folded position.

10 and 11 represent two pair of legs which are attached solidly by means of bolts 12 and 35 13 or other fastening members, to two U shaped bars 14 and 15 respectively. Into two grooves 16 and 17 which are formed by the U shaped bars 14 and 15 there is inserted the ends of the toilet seat 18. This 40 toilet seat is made of a rectangular piece of canvas or other suitable material, having an aperture or opening 19. The ends of the legs 10 and 11 and the ends of the seat are inserted into the grooves 16 and 17. The 45 bolts 12 and 13 pass through the ends of the legs, the bars, and the ends of the toilet seat. The seat is thereby solidly secured to the bars within their grooves. In order to further secure the canvas to the bars, the 50 sides of the bars may be pressed together tightly or the canvas may be sewed around the bars, thereby securing the canvas along their entire ends.

To the top of the toilet seat at 20, I attach 55 one end of a rectangular piece of canvas 22 or other suitable material. The other end

of the canvas, which is used for a seat is detachably connected by means of buttons 21 or other fastening members. This seat 22 when buttoned or fastened and used as a seat 60 is shorter than the toilet seat. This is done for the reason that when the device is used as an ordinary seat, the entire weight comes directly on the seat 22.

The legs 11 are reenforced by a rod 23 connecting the two legs solidly. The legs 10 are reenforced by bars 24 and 25 connecting the legs to the bar 14.

To the back of the flap 18 I may attach 65 a pocket or container for toilet paper. The 70 pocket will be so arranged that it fits into the hole 19. I may also provide the chair with a back like an ordinary chair. I may also provide a container to be attached underneath the opening to receive the ex- 75 cretion.

The opening 19 is reenforced by inserting 80 along its edge and enclosed with the cloth, which is cut bias, a semi-pliable material, to give it strength and form and also to allow it to be folded when the chair is folded. I may also strengthen the toilet seat by inserting the same semi-pliable material along the edges of the toilet seat and enclosed 85 within the cloth.

From this it will be seen that when the top seat is attached to the chair by means of the buttons or fastening member, then the chair is used as an ordinary camp chair. The weight of the person coming directly on the top seat or flap. If, however, it is to be used as a convenience chair, the top cover or flap is detachable and folded or thrown back, exposing the toilet seat and in position to be used as a toilet seat.

Having described my invention, what I claim is:

A camp convenience chair consisting of two pair of legs, means permitting it to be used as a toilet seat consisting of two U shaped bars to which each pair of legs is connected, a rectangular piece of canvas with an aperture therein solidly connected to the U shaped members, and means permitting it to be used as a chair, without exerting any pressure on the toilet seat, consisting of a rectangular piece of canvas solidly connected on one side to the canvas of the toilet seat and detachably connected to the opposite end of the chair, said seat being shorter than the corresponding part of the toilet seat.

JOHN HARRISON.
